LADY'S STOCKING

Charles J. Bossong, 834 Shamrock Road,
Asheboro, N.C.

Filed July 22, 1965, Ser. No. 86,260

Term of patent 14 years

(Cl. D47—7)

FIG. 2

FIG. 1 is a side elevational view of a lady's stocking embodying my new design the opposite side being a mirror image thereof and the welt portion being conventional; and

FIG. 2 is an enlarged fragmentary view of a portion of the stocking shown in FIG. 1.

I claim:

The ornamental design for a lady's stocking, as shown and described.
